Primary Examiner—Terry A. Wallace(74) *Attorney, Agent, or Firm*—Jenkens & Gilchrist(57) **CLAIM**

The ornamental design for a lid for a bowl, as shown.

DESCRIPTION

FIG. 1 is a perspective view of a lid for a bowl.

FIG. 2 is a top view of a lid for a bowl.

FIG. 3 is a bottom view of a lid for a bowl.

FIG. 4 is a front-side view of a lid for a bowl.

FIG. 5 is a back-side view of a lid for a bowl.

FIG. 6 is a left-side view of a lid for a bowl; and,

FIG. 7 is a right-side view of a lid for a bowl.
